LOOM AND THE METHOD OF WEAVING
THEREON

Racine F. Caron, Moosup, Conn.

Application February 12, 1938, Serial No. 190,154

16 Claims. (Cl. 139—49)

This invention relates to the method of and mechanism for embroidering a pattern in fabric on a loom and has for an object to provide a simple mechanism which can be readily attached to standard looms. This application is a continuation-in-part of applicant's copending application Serial No. 143,430.

A further object is to provide a loom with one or more members having needles therein for guiding the pattern thread.

A further object is to provide a loom with a plurality of needles carried on the lay so that the pattern thread may be crossed by the filler thread and beat into the fabric.

15 A further object is to provide a loom with mechanism for automatically shifting one or more needle bars either simultaneously, intermittently or alternately as the pattern may require.

20 A further object is to provide a loom with a needle bar and a plurality of oscillatable thread guides whereby a multiple strand pattern thread may be braided into the fabric.

25 A further object is to provide a loom with a plurality of needles and a pair of oscillatable thread guides for each needle so that one strand of the pattern thread may be crossed by the filler thread and beat into the fabric and subsequently the said strand crosses over the two strands of the pattern thread carried by the 30 thread guides whereby a braided pattern thread is woven into the fabric.

35 A further object is to provide means on a loom whereby patterns employing either a single thread or a plurality of threads may be woven into the warp and held therein by the filler thread.

An embodiment of the invention is illustrated by the way of example in the accompanying drawings in which:

40 Fig. 1 is an end elevation of a loom equipped with the mechanism of the invention.

Fig. 2 is a partial front elevation of a loom showing the mechanism of the invention.

45 Fig. 3 is a detail section taken on line 3—3 of Fig. 2 showing the intermittent driving mechanism for the pattern chain.

Fig. 4 is a detail section taken on line 4—4 of Fig. 2 showing the pattern chain.

50 Fig. 5 is a section taken on line 5—5 of Fig. 1 showing the mounting of the needle bar actuating levers.

Fig. 6 is a plan section taken on line 6—6 of Fig. 1 showing the needle bars.

55 Fig. 7 is an elevational section taken on line

7—7 of Fig. 2 showing the mounting of the needle bars.

Fig. 8 is a schematic view showing the position of the needles and the pattern thread at each beat of the loom.

Fig. 9 is a schematic view showing the position of the needles and the pattern thread at each pick of the loop.

Fig. 10 is a schematic view illustrating the movement of the pattern thread in forming a 10 design.

Fig. 11 is a partial front elevation of a loom incorporating a modification of the invention.

Fig. 12 is an enlarged view of a portion of Fig. 11 showing the assembled construction of the 15 modification.

Fig. 13 is an elevational section looking in the direction of arrow 13 of Fig. 12.

Fig. 14 is a detail section taken on line 14—14 of Fig. 11.

Fig. 15 is a schematic view showing a position of the needles and thread guides on the pick of the loom.

Fig. 16 is a schematic view showing an alternate position of the needles and thread guides 25 on the pick of the loom.

Fig. 17 is a schematic view illustrating the formation of the pattern braid and the tie thereof in the fabric.

Like numerals refer to like parts throughout 30 the drawings.

Referring to Fig. 1 the frame 1 represents a loom of standard construction, used throughout the weaving industry, having the usual rockshaft 2 upon which is mounted the lay 3, the said lay 35 being oscillated in the usual manner by means of a lever 4, Fig. 2, attached to a crank 5. The crank is mounted on a shaft 6 having a pair of pulleys 7, tight and loose, for driving the loom. Power is applied to the tight pulley from any 40 suitable source such as a motor 8.

A sprocket 9, fastened to shaft 6, is geared to a sprocket 10, Fig. 3, by means of a chain 11. The sprocket 10 is non-rotatably mounted on a shaft 12 to which is also fastened a driving 45 disc 13 having a stud 14 inserted therein, said stud engaging a slot in a Geneva gear 15 which is non-rotatably mounted on a shaft 16. The shaft 16 is connected to a shaft 17 by means of a clutch 18, the said clutch being held in driving 50 engagement by means of a lever 19. Non-rotatably mounted on the shaft 17 is one or more sprockets 20 for driving one or more pattern chains 21. A corresponding number of idler sprockets 22 are rotatably mounted on a shaft 55

23 mounted in bearings provided by a bracket 24 suitably fastened to the side frame of the loom.

The shafts 16 and 17 are mounted in bearings 25 and 26 which have extensions 27 and 28 in which are bearings to support a shaft 29 on the outer end of which is mounted one or more levers 30. The levers 30 have rollers 31 which contact the pattern chains 21 whereby the said levers are given an oscillating motion.

10 So far the mechanism described is found in any standard loom and need not be further elaborated upon except to say that when the power is applied to the loom through the tight pulley 7 the crank 6 is rotated whereby the lay 3 is 15 oscillated by means of the lever 4.

At the same time the chain 11 rotates the driving plate 13 and stud 14, said stud turning the Geneva gear 15 to advance the pattern chain in a step by step motion to oscillate the levers 20 30. During this time the harness is being operated in the usual manner by suitable head mechanism, not shown, to form the shed in the warp as shown diagrammatically in Figs. 8 and 9.

The type of heddle operated by the harness is 25 immaterial and forms no part of this invention as any type of heddle may be used depending on the weave desired.

The levers 30 have a member 39' adjustably mounted thereon which provides an extension 30 32 having a pin 33. Fulcrumed on the pin 33 is a member 35 having a screw threaded end in which is screw threaded a rod 36, said rod being held in adjusted position by means of a lock nut 37. The other end of the rod is fulcrumed 35 on a pin 38 provided in an adjustable member 39 mounted on a lever 40. The number of levers 40 will correspond to the number of levers 30.

Referring now to Fig. 5 it will be noted that the levers 40 are mounted on one end of a series 40 of telescoping shafts 41, 42, 43, and 44. The shaft 41 supporting all of the other shafts and being itself mounted in bearings 45 and 46 which are in turn mounted on a bracket 47 fastened to the main frame 1. On the other end of the 45 shafts 41, 42, 43, 44 is mounted a series of levers 48. By thus mounting the said levers each pair of levers on the several shafts are actuatable independently of the other pairs of levers.

On the levers 48 is adjustably mounted a member 49 having a fulcrum pin 50 on which is hung 50 a member 51, said member being screw threaded to receive the screw threaded end of a rod 52 which is held in position by means of a lock nut 53. The lower end of the rod or rods 52 has 55 an eye 54 which engages with an eye 55 on the end of a short belt 56 which passes around a pulley 57. On the other end of the belt is an eye 58 which mates with an eye 59 on the end of a rod 60.

60 The rod 60 is fulcrumed on a pin 61 fastened in one arm 62 of a bell crank lever 63 which is rockably mounted on a shaft 64 carried in bearings in a bracket 65 fastened to the lay 3. The other arm 66 of the lever 63 has a pin 67 fastened therein on which is fulcrumed one end of a rod 68 the other end of which is fulcrumed on a pin 69 carried in one arm 70 of a two armed lever 71 rockably mounted on a stud 72. The other arm 73 of the lever 71 has a pin 74 on which 65 is fulcrumed a rod 75, said rod having two threaded parts joined by a turnbuckle 76 whereby the length of the rod can be adjusted. The other end of the rod 75 is rockably mounted on a stud 77 carried by a block 78 the said block 76 being adjustably fastened to a needle bar 79

having a plurality of needles 80 having eyes therein. The needles are readily removed from the bar as they are held therein by a screw 80'.

As shown in the drawings the needle bars are made of single solid pieces but this is by the way of illustration and not of limitation as it is within the purview of this invention to use flexible means to hold the needles.

The needle bar or bars 79, Figs. 6 and 7, are slidably mounted on a V shaped bar 81 extending 10 longitudinally of the lay while the said bar 81 is mounted for vertical movement relative to the lay 3 on V shaped bars 82, there being V shaped bearings 83 on each end of the bar 81 which slidably fit the bars 82. The bars 82 are fastened to the lay in any suitable manner.

In order to guide the vertical movement of the bar 81, and hence the needle bars, the said bar has a roller 84 at each end which fits in guideways 85, Fig. 1, provided in brackets 86 20 and 87 suitably fastened by means of screws 88 to the side frames 1. A slot 89, in the brackets 86 and 87, through which the screws pass make it possible to adjust the said brackets in relation to the lay.

The spools of pattern thread 90 for the needles are mounted on a member 91 fastened to the side frames and the threads enter from the rear of the loom through the reed to the needles while the warp threads come from the rear of the loom 30 through the heddles and reed in the usual manner. The filler thread is carried in a shuttle 92 which is driven back and forth across the race 93 on the lay 3 in the shed by the picker staff 35 94, Fig. 2, which is driven by the usual picker cam 95 and lever 96 which lever is connected to the picker staff by a link 97 such mechanisms being old and well known in the art and need not be further described.

The operation of the invention will now be 40 described. The operator starts the loom in the usual manner by slipping a belt from the loose pulley 7 to the tight pulley 7 and throws in the clutch 18 by means of the lever 19. Rotation of the shaft 6 will cause the crank 5 to rotate and, 45 through the lever 4, oscillate the lay 3. At this time the harness will be operated to form the shed for the passage of the bobbin with the filler thread.

Movement of the harness also causes movement of the particular type of heddle being used to guide the warp threads. In the instant case heddles suitable for weaving a standard leno weave are used but as they form no part of the invention, being old and well known in the art, 55 they need not be further described.

Rotation of the shaft 6 also rotates the shaft 12, through the chain 11, and hence the pattern chain 21 through the Geneva gear 15 and sprocket 20. As the pattern chain moves certain of the 60 links lift the lever 30 and through the rod 36, levers 40 and 48, rod 52, belt 56, rod 60, bell crank lever 63, rod 68 and lever 71 moves the needle bar 79 longitudinally of the lay a distance determined by the pattern link.

As above described the pattern chain and associated needle bar actuating mechanism has been spoken of as a single unit but it is to be fully understood that there can be a plurality of these mechanisms and chains to operate a 70 number of needle bars whereby an infinite number of patterns may be formed simultaneously.

As the lay 3 oscillates to the left, Fig. 1, or to the right in Fig. 7, the needle bar supporting bar 79 moves down the guide ways 85 in the brackets 75

86 and 87 and lowers the needles 80 so that the threads from the spools 90 will be among the lower threads of the shed whereby the shuttle may pass over the threads and secure them into the fabric at each beat. Referring to Fig. 10 it will be seen that the pattern thread 90 is moved longitudinally over the upper threads of the shed just prior to the pick when the filler thread 98 is thrown through the shed to catch the portion of the thread 90 into the fabric. As the lay comes up on the beat stroke the needles move up above the warp and back to carry the pattern threads longitudinally over the strands of the warp.

15 The longitudinal movement of the pattern threads is governed entirely by the pattern chain or chains so that they may be moved over one strand of the warp on one pick and over two or more on the next pick. When two or more needle bars are used the variety of patterns obtainable is practically unlimited and also the fact that the needles are readily removable the combinations of patterns obtainable from each needle bar are extremely great.

25 Fig. 10 shows, for purposes of illustration and not of limitation, a standard leno weave into which a pattern is being woven. It is clearly apparent that this invention can be used for weaving patterns into any species of weave that is obtainable on the type of loom illustrated.

The modification of this invention as illustrated in Figs. 11 to 17 inclusive shows that instead of weaving a plurality of single pattern threads into the fabric it is possible to weave 35 a braided pattern thread into a fabric in such a manner that should one or more warp threads break the pattern will remain in position.

With the mechanism of this modification it is also possible to weave a fabric having a warp 40 consisting entirely of braided threads.

Referring to Fig. 11 the tight and loose pulleys 100, corresponding to the pulleys 7, of Fig. 1, cause oscillation of the lay 101, through suitable connections such as above described, and drive 45 a chain 102 which is geared to a shaft 103 having a driving disc 104 which in turn drives a Geneva gear 105. The gear 105 is non-rotatably mounted on a shaft 106 which is connected to a shaft 107 by means of a clutch 108, the said 50 clutch being held in driving engagement by means of a lever 109. A sprocket is non-rotatably mounted on the shaft 107 to support a pattern chain 110. The shafts 106 and 107 are mounted in bearings provided by brackets 111 and 112 having extensions 113 and 114 which 55 have bearings thereon for supporting a shaft 115. Upon the shaft 115 is loosely mounted a plurality of levers 116, 117, 118. The lever 116 provides a connection between the pattern chain 110 and 60 a lever 119 which is non-rotatably mounted on one end of a shaft 120 supported in a bearing 121. A lever 122 is non-rotatably mounted on the other end of the shaft 120 and transmits the motion of lever 120 to a bell crank lever 123 65 through rods 124 in the manner shown in Fig. 1. The bearing brackets 111 and 112 are mounted on an extension 125 while the bearing 121 is mounted on a bracket 126 both of which are suitably fastened to the side frame of the loom.

70 The bell crank lever 123 is connected by a rod 127 to a rock lever 128 which in turn is connected to a member 129, said member being slidably mounted on a bar 130. The bar 130 is slidably 75 mounted in vertical bearings fastened to the

lay whereby the said bar is moved vertically relative to the lay at each beat of the loom.

The member 129 has fastened thereto a needle bar 131 having a plurality of needles 132 adjustably mounted therein. As above described 5 as the pattern chain is advanced the needle bar 131 is moved longitudinally of the lay.

On the reed cap 133, Figs. 12 and 13, is slidably mounted a pair of bars 134, 135 having slots 136 to allow the bars to move longitudinally 10 of the reed cap.

Studs 137 hold the bars to the reed cap and provide the bearing guides for the bars. A member 138 connects the needle bar 131 and the bars 134 and 135 whereby the said bars are moved 15 longitudinally of the lay in response to the longitudinal movement of the needle bar. The member 138, fastened to the bars 134 and 135 by means of a screw 139, has an elongated slot through which is passed a screw 140 whereby the 20 needle bar 131 may move vertically relative to the bars 134 and 135. With this construction the needle bar can move the said bars, longitudinally of the reed cap regardless of its vertical position. 25

Each of the bars 134 and 135 have a plurality of thread guides 141 and 142 respectively which are mounted on pivot pins 143 and 144, Fig. 13, the spacing between the said pivot pins corresponding to the spacing between the needles 132 30 35 whereby the pivot points of the thread guides and the needles are retained in alignment at all times.

The top of each of the thread guides 141 and 142 has a fulcrum pin 145 and 146 therein to 35 which are attached bars 147 and 148. Each of the bars 147 and 148 are connected by means of Bowden cables 149 and 150, Fig. 11, to levers 117 and 118 respectively. The levers 117 and 118 are moved by means of cams 151 and 152, Fig. 40 40 45 14, mounted on the shaft 103. The cams are shaped so as to give the desired movements to the bars 147 and 148 whereby the thread guides 141 and 142 may be oscillated in opposite directions as shown in Fig. 15 or they may be oscillated together as shown in Fig. 16.

When the thread guides are oscillated as in Fig. 15 the pattern threads 153, 154 and 155 are crossed in the manner shown in Fig. 17. In this figure the pattern threads are shown being woven 50 into a fabric known as a leno weave but the species of weave used in conjunction with the pattern threads is immaterial so long as it can be woven on a loom of the type described.

When the operator starts the loom the lay 55 swings back for the first pick at which time the needle bar 131 and needles 132 are lowered so that the thread 153 is placed on the lay and crossed by the filler thread after which the filler thread is beat up and the needles are raised and 60 the cams 151 and 152 move the bars 147 and 148 whereby the thread guides 141 and 142 oscillate left and right respectively to cross the threads in back of the thread 153. On the next pick of the loom the needles 132 are again lowered so that the thread 153 can again be crossed by the filler thread and when the needles are raised this time the thread guides 141 and 142 65 oscillate right and left respectively, this is just the opposite of the first oscillation, after which 70 the filler thread is beat up.

It is to be noted that the threads carried by the needles are always crossed by the filler thread and cross over the threads 154 and 155 whereby a braid is woven into a fabric. With this inven- 75

tion the entire warp can consist of braided threads held in shape by the filler threads.

In cases where it is desirable to have the braided pattern threads advanced diagonally

5 back and forth across the width of the fabric the needles 132 and thread guides 141 and 142 are moved longitudinally of the lay in response to the cams on the pattern chain whereby geometric figures can be woven into the fabric by

10 means of the braided pattern threads.

I claim:

1. In a loom, a reed, a pair of bars mounted on the reed for longitudinal movement relative thereto, a plurality of pivot pins on each of said bars, and a thread guide mounted on each of said pivot pins whereby threads carried by said guides are crossed over each other upon the relative movement of said bars.

20 2. In a loom, a reed, a pair of bars mounted on the reed, a plurality of thread guides pivotally mounted on the bars, and means for moving said bars longitudinally of the reed whereby said thread guides are oscillated to cross threads carried thereby.

25 3. In a loom, a reed, a pair of bars slidably mounted on said reed, a plurality of thread guides pivotally mounted on each of the bars, each of said thread guides having a fulcrum bearing, a pair of bars having a plurality of fulcrum pins 30 on which said thread guide fulcrum bearings are mounted, and means to move said pairs of bars relatively to each other to oscillate said thread guides.

35 4. In a loom, a reed, a pair of bars slidably mounted on said reed, a plurality of thread guides pivotally mounted on each of the bars, a pair of bars having a plurality of fulcrum pins on each bar on which the thread guides are mounted, and means to move the second pair of bars relative to the first pair of bars whereby the thread guides are oscillated.

40 5. In a loom, a lay, a reed, a needle bar mounted on the lay, a plurality of needles in said bar, means to move the needle bar longitudinally of said lay, a pair of bars mounted on said reed, and means to move said bars longitudinally of said reed in response to the longitudinal movement of said needle bar whereby threads carried by said needles and guides are braided.

45 6. In a loom, a lay, a reed, a pair of bars slidably mounted on said reed, a plurality of thread guides pivotally mounted on each of the bars, a needle bar slidably mounted on said lay, a plurality of needles mounted in said needle bar, means to move the needle bar longitudinally of the lay, and means to maintain the fulcrum points of the thread guides in line with the needles.

50 7. In a loom, a lay, a reed, a needle bar mounted on the lay, means to move the needle bar longitudinally of the lay, a pair of bars mounted on the reed, means to move the needle bar vertically of said lay and relative to said bars, means to move said bars longitudinally of said reed in response to the longitudinal movement of said needle bar, and means provided by said last named means to permit the relative vertical movement between the needle bar and said bars.

55 8. In a loom, a lay, a reed, a needle bar mounted on the lay, a plurality of needles mounted in said needle bar, a pattern chain, means to drive said chain, means actuated by said pattern chain including a train of links and levers to move said needle bar longitudinally of said lay, a pair of bars slidably mounted on the reed, a plurality of

60 oscillatable thread guides mounted on said pair of bars in line with said needles, and means to move said bars coincidentally with the needle bar whereby the thread guides remain in line with the needles.

65 9. In a loom, a lay, a reed, a needle bar mounted on the lay, a plurality of needles mounted in the needle bar, a pattern chain, means to drive said chain, means actuated by said pattern chain including a train of links and levers to move the 70 needle bar longitudinally of the lay, a pair of bars slidably mounted on the reed, a plurality of thread guides pivotally mounted on each of said last named bars, said thread guides having fulcrum bearings above the pivot points, a pair of 75 bars providing fulcrum pins for each of the thread guides, and means including a cam for moving said last named bars relative to said first named bars whereby the said thread guides are oscillated in timed relation to the movement of 80 the needle bar.

85 10. In a loom, a lay, a reed, a needle bar mounted on the lay for longitudinal and vertical movement relative thereto, means to move said needle bar longitudinally of the lay, a pair of bars having a plurality of thread guides pivoted thereon, a second pair of bars having fulcrum pins mounted on the thread guides, means to move said first pair of bars in response to the longitudinal movement of the needle bar to maintain the 90 pivots of the thread guides in line with the needles, and means to move the second pair of bars to oscillate the thread guides.

95 11. In a loom, having a lay, a reed, a pattern chain, means to oscillate said lay and move said chain, a shuttle, and means to actuate said shuttle, in combination with a braiding device comprising a needle bar having a plurality of detachable needles therein, a plurality of oscillatable thread guides, a plurality of spools of thread, one for each needle and guide, means to move said needle bar longitudinally of said lay, means to move said guides in response to the movement of said needle bar, means to move said needle bar vertically of said lay whereby the threads carried by the needles will rest on the lay in order that the shuttle may pass over them, and means to oscillate the thread guides relative to the needles.

100 12. The method of weaving a braid into a piece of goods which consists in crossing two strands of the braid under a third strand which is subsequently laid on the lay and a filler thread passed over it.

105 13. The method of weaving which consists in shedding a warp so that a plurality of single threads form the lower strands and a plurality of double threads form the upper strands, passing a filler thread over the lower strands, crossing the upper threads under the lower, and beating the 110 filler thread into the warp.

115 14. The method of weaving which consists in laying a plurality of threads by means of needles among the lower threads of the warp at each pick of a loom, raising the said plurality of threads and crossing a pair of threads in back of each of said plurality of threads at each beat of the loom so that a number of braids are woven into a fabric.

120 15. The method of weaving which consists in forming a braid and tying it into the goods by means of the filler thread at each pick of the loom.

125 16. The method of weaving which consists in shedding a warp, laying a single strand of a braid 130

by means of needles among the lower strands of the warp in the shed, passing a filler thread in front of the needles and over said lower strands including the single strand, beating the filler thread into the warp and raising the single strand above the warp, crossing two strands of the braid

behind the single strand, moving the three strands of the braid over the warp to form part of a pattern and repeating the process over and over until the pattern is completed several times throughout the fabric being woven.
